UNITED STATES PATENT OFFICE.

JOHN WILLIAM RUTLEDGE, OF SHANNONDALE, INDIANA.

GATE.

SPECIFICATION forming part of Letters Patent No. 380,636, dated April 3, 1883.

Application filed October 11, 1887. Serial No. 252,094. (No model.)

To all whom it may concern:

Be it known that I, JOHN WILLIAM RUTLEDGE, of Shannondale, in the county of Montgomery and State of Indiana, have invented a new and useful Improvement in Gates, of which the following is a specification.

My invention is an improvement in gates; and it consists in certain features of construction and novel combinations of parts, as will be hereinafter described and claimed.

In the drawings, Figure 1 is a perspective view of my improvement, the gate proper being shown closed in full lines and open in dotted lines. Fig. 2 is a detail view of one end of the gate, showing the latch mechanism, the motion thereof being indicated in dotted lines. Fig. 3 is a detail view of the rear upper edge of the top gate-bar, showing the lever in position thereon; and Fig. 4 is a detail section on about line *x x*, Fig. 2.

The hinge-post A and the latch-post B are bolted securely to the mud-sill C, which latter is sunk into the ground and extends at its ends past the posts A and B, as shown in Fig. 1. To the mud-sill, immediately in rear of the posts, I secure the cross-sills D, which extend to opposite sides of the mud-sills, and the posts A and B are braced firmly in position by means of strut-braces *a*, which extend from the posts to the mud-sills and the cross sills, as clearly shown in Fig. 1.

On the inner face of the latch-post B, I provide, usually by means of a cleat, *b*, a notch, *E*, to receive the point of the latch, presently described, and similar notches are provided on posts F, placed alongside the roadway or approach to the gate, and on opposite sides of the latter. I also provide pulley-supporting posts G, which serve as guides for the operating-cords *g*, which are passed over the guide-pulleys of the posts G and depend therefrom at one end, having such ends provided with knobs or hand-holds, which may be short chains, if desired. The gate proper, II, is hinged at one end to the hinge-post A, and has its top bar, *h*, extended at I beyond the hinge-post. The latch J is movable at one end past the swinging edge of the gate, being supported in suitable guides, and being actuated by coil-spring *j*, which serves to force the latch normally out-

ward to enter the notches E of the latch-post or of the posts F.

To the gate below the latch I pivot one end of a lever, K, which extends up past and engages said latch—usually by being pivoted thereto—and projects upward above the gate, extending preferably through a keeper-slot, *k*, the walls of which operate to guide and properly limit its movement. To the upper end of this lever is connected a wire, rod, or cord, L, 60 preferably a wire, as shown, which extends along the top of the gate toward and past the hinge thereof, and is connected at its opposite end with the main arm *m* of a triple armed or Y-shaped lever, M.

The guides *l*, provided on the gate for the connection L, insure the movement of such connection in a straight line and in line with the top of the gate. This construction avoids any drawing of the upper end of lever K to 70 either side by the turning of lever M on its pivot, and thus renders the operation of the latch easy and certain, as will be seen. It will be readily understood that if the connection between the lever K and the lever M were not 75 guided and held in line with the top of the gate the movement of the arm *m* of lever M to one side or the other would operate in a measure to draw the upper end of lever K to one or the other side, causing the said lever 80 K, in a measure, to bind, and to such extent impeding its action.

The lever M has the main arm *m* and the branches or arms *m'* diverging at equal angles from the main arm, and the lever is pivoted at 85 the juncture of its said arms to the rear extension, I, of the gate. The operating-cords *g* connect with the branches *m'*, the several parts being arranged as clearly shown in Fig. 1.

The triple-armed lever is especially desirable, the rear branches, *m' m'*, projecting to opposite sides and connecting with the cords *g* on such sides. By reason of these two arms, it will be seen that whether one or the other of the branches *m'* be drawn upon it will first tilt the 90 lever M slightly to open the latch, which slight movement will bring the branch *m'* into line with the connection *g*, when drawing on said cord will not operate further to turn the lever, except such slight turning as results from the 95 100

change of position of the gate in the opening and closing thereof.

In operation, a person approaching the gate—say in the direction indicated by the arrow, 5 Fig. 1—by drawing on the cord *g* will tilt the lever so as to first move the latch out of the notch *E* of the latch-post, and then turn the gate on its hinge, when it will move open in the direction away from the approaching person, and, when at its extreme open position will engage, by its latch, with and be held by the post *F*. By drawing on the operating-cord on the opposite side of the gate it will be moved to the closed position and be held by the notch 15 of the latch-post. It will be seen that whether the person approach the gate from one side or the other it will open away from him, as is desired.

Manifestly while the connection between the 20 main arm of the triple-armed lever and the latch is effected through the intervention of the lever *K* such lever might be omitted without departing from some of the broad features of my invention.

25 Having thus described my invention, what I claim as new is—

1. The combination of the hinged or pivoted gate having a latch and suitable supporting-framing, the lever *M*, pivoted on the gate off

the hinge or pivotal center thereof, and having arm *m*, and arms *m' m'* diverging from the rear end of arm *m*, the angles of both said arms *m' m'* to the arm *m* being approximately the same, a connection, *L*, uniting the arm *m* with the latch, and operating-cords connected 30 with the arms *m'*, substantially as set forth.

2. The combination of the gate, hinged or pivoted and provided with a rearwardly-projected extension, the latch, the triple-armed lever pivoted on the rear extension of said gate, the connection between the main arm of 35 said lever and the latch, and the operating-cords connected with the branches of said lever, substantially as set forth.

3. The combination of the gate having a 40 rear extension, *J*, and provided with guides for the latch, the latch movable in said guides past the swinging edge of the gate, the lever pivoted to the gate below the latch, extended up past and engaged with the latch and projected 45 above the gate, the triple armed lever pivoted on the rear extension of the gate, and the operating-cords, substantially as set forth.

JOHN WILLIAM RUTLEDGE.
